Attorney

UNITED STATES PATENT OFFICE.

SADIE C. WINFREY, OF NORPHLEAT, ARKANSAS.

ROTARY TRIP TONG.

Application filed August 24, 1925. Serial No. 52,168.

This invention relates to new and useful improvements in a rotary trip tong.

One object of the invention is to provide a tong of the character described adapted to be applied to a drill stem or other tubing in a well bore, and to be operated by the rotary table, and which is so constructed that it will transmit only a predetermined torsional strain to the stem, or tubing, and thus protect the tong against breakage and the stem, or tubing, and coupling connecting the sections thereof against crushing or bursting.

With the above and other objects in view this invention has particular relation to certain novel features of construction, operation, and arrangement of parts, an example of which is given in this specification and illustrated in the accompanying drawings, wherein:

Figure 1 shows a fragmentary plan view of a rotary table, showing the tong applied to the pipe and in operative connection with the table, and

Figure 2 shows a front elevation of the tong.

Referring now more particularly to the drawings, wherein like numerals of reference designate similar parts in each of the figures, the numeral 1 designates the rotary table, and the numeral 2 designates the drill stem, or other pipe, which extends through the central opening of the table and down into a well bore.

The tong includes a handle, which is formed of the sections 3, and 4, jointed together. Secured to opposite sides of the free end of the section 4 are the serrated, pipe engaging jaws 5, 5. A chain 6 is fastened, at one end, to the front side of the handle, adjacent said jaws, and this chain is adapted to be passed around the pipe, and between the jaws, and its other end may be secured to the hook 7 carried by the back side of the handle.

Bearings 8, 8 are secured to the front side of the handle, on opposite sides of the joint thereof, and a jointed rod formed of the sections 9, 9, works through said bearings. The ends of this rod are threaded and receive the nuts 10, 10 and interposed between these nuts and the respective bearings 8, 8, and surrounding said rod are the strong coil springs 11, 11.

The joints of the handle and rod are aligned and are one way joints, being formed to break backwardly only.

In application the tong is applied to the pipe, in the usual way. The conventional back up post 12, carried by the rotary table, operates against the outer section 3, of the tong handle, to revolve the tong and turn the pipe to which the tong is applied. The upper section of the pipe (not shown) is held against turning by means of a suitable tong which is held stationary, in the usual way. As the rotary table turns the joint connecting said section to the string of pipe is screwed up, or broken. In case the joint cannot be broken by the application of a torsional strain which the tong, or pipe will stand the springs 11, 11, will yield to permit the joints connecting the handle sections 3 and 4 and the rod sections 9, 9, to break and the back up post 12 to pass, thus preventing the breakage of the tong and the bursting of the connecting coupling or the crushing of the pipe.

When the back up post has passed the pressure of said springs will immediately restore the tong to operative position so that upon the completion of each rotation of the table the back up post will again engage the tong and subject the pipe to another torsional strain, and so on until the joint is broken.

What I claim is:

1. A tong including a handle formed of sections jointed together, bearings carried by the handle, one on each side of the handle joint, a jointed rod working through said bearings, abutments on said rod, one on each side of the joint thereof, yieldable members interposed between the respective bearings and the corresponding abutments.

2. A tong including a handle formed of sections jointed together, bearings carried by the handle, one on each side of the handle joint, a jointed rod working through said bearings, abutments on said rod, one on each side of the joint thereof, yieldable members interposed between the respective bearings and the corresponding abutments and pipe engaging means carried by the handle.

In testimony whereof I have signed my name to this specification.

SADIE C. WINFREY.
